UNITED STATES PATENT OFFICE.

CARL H. ZWERMANN, OF KALAMAZOO, MICHIGAN.

FLUSH-TANK VALVE OF THE DIAPHRAGM TYPE.

1,097,501.

Specification of Letters Patent.

Patented May 19, 1914.

Application filed December 3, 1913. Serial No. 804,428.

To all whom it may concern:

Be it known that I, CARL H. ZWERMANN, a citizen of the United States, residing at Kalamazoo, Michigan, have invented certain new and useful Improvements in Flush-Tank Valves of the Diaphragm Type, of which the following is a specification.

This invention relates to improvements in flush tank valves of the diaphragm type.

10 The objects of the invention are: First, to provide a flush valve of the diaphragm type which is operated by direct mechanical connection to the valve lid. Second, to provide a valve of this type which will operate effectively when the flush tank is only partially filled.

Further objects and objects relating to details and economies of construction and operation will definitely appear from the 20 detailed description to follow.

I accomplish the objects of my invention by the devices and means described in the following specification.

The invention is clearly defined and 25 pointed out in the claims.

A structure which is a preferred embodiment of my invention is clearly illustrated in the accompanying drawing forming a part of this specification, in which—

30 Figure I is an elevation of my improved valve shown in connection with a flush tank, part of which is broken away for convenience of illustration. Fig. II is a vertical longitudinal sectional view through the 35 valve structure. Fig. III is a transverse sectional view on line 3—3 of Fig. II. Fig. IV is a sectional view on line 4—4 of Fig. II, a part of the supporting ring being broken away. Fig. V is an elevation of a 40 modified form of construction, part of the flush pipe being broken away to show details of the lever and connections. Fig. VI is an enlarged detail sectional view on the line 6—6 of Fig. V, showing in detail, the 45 connection of the operating lever.

In the drawing similar reference characters refer to similar parts throughout the several views, and the sectional views are taken looking in the direction of the little 50 arrows at the ends of the section lines.

Considering the numbered parts of the drawing, 1 is the outer flush tank casing which is provided with the top 2 and in which the inner casing 3 is supported. 4

is the supply valve which is controlled by 55 the float 5, all in the usual or any desired form.

Disposed in a suitable opening in the bottom of the tank is the coupling 9 provided with the valve seat 9' at its upper end. 60 This coupling is provided with a number of radiating arms, having the upstanding projections 10 to which the ring 8 is integrally secured.

7 is the dome shaped upper casing provided at its periphery with an annular flange resting upon said ring and secured thereto.

15 is a diaphragm of sheepskin or other pliable material secured at its periphery 70 between the flange of the casing 7 and said ring 8, by the screws 11 which hold these parts together. These two parts form a chamber of which the diaphragm valve is the movable lower wall.

75 Opening out of and secured to the upper central part of the casing 7 is the siphon column 6 which is sealed at its upper end. The diaphragm valve comprises the diaphragm 15 and the disks 13 and 16 disposed 80 above and below the same. The disk 13 is provided at its center with an upstruck annular flange.

12 is the siphon discharge pipe to which is secured, at its lower end, a screw threaded coupling 12' which is threaded into corresponding screw threads in the flange on the disk 13. The lower end of this coupling passes through the disk 13 and an opening in the diaphragm 15 and projects 90 beneath the same through an opening in disk 16.

18 is the lower section of the discharge pipe to which is secured the coupling 17 which threads upon the screw threaded end 95 of the coupling 12' on the pipe 12, and clamps the parts of the diaphragm valve together. This provides a water tight joint through which the siphon discharge pipe 12 passes.

100 The disk 13 is provided with a number of upstruck projections 14 which engage the top of the casing 7 when the valve is lifted so as to prevent the disk 13 from sealing the upper part of the chamber. The siphon discharge pipe 12 extends upwardly into the siphon column 6 and terminates near the top of the latter.

The chamber 7 is provided with a somewhat restricted inlet opening 7', and with a suitable opening through which the operating rod 19 passes, which opening might 5 be sufficiently large to serve the purpose of opening 7'. This rod is secured to the upper disk of the diaphragm valve and it is lifted by means of the link 20 connected thereto and connected at its upper end to 10 the operating lever 21 which is manipulated by means of a handle 22.

In Figs. V and VI I have shown a modification in which the valve is operated from beneath. In this form, a rod 19' is secured 15 to the lower disk and is provided with the laterally offset end engaging in a slot 27' in the upper end of the link 27. A stuffing box 24 is provided in the side wall of the flush pipe 23 and an operating shaft 25 is 20 journaled in said stuffing box. On the inner end of said operating shaft is secured the crank arm 26 which is connected to the lower end of the link 27. 22' is a handle 25 for operating the same which is secured on the outer end of the crank shaft.

From the description of the parts given above the operation of the valve will be very readily understood. Normally the water in the tank is kept at a level below the top of 30 the siphon discharge pipe 12, and the siphon column 6 is filled to a point at a level with the water in the tank. When the diaphragm valve 15 is lifted, the water in the chamber 7 is forced up into the siphon column 6 so as to raise the level of the water 35 therein above the top of the siphon discharge pipe 12. It will be seen that the siphon column 6 and the discharge pipe 12 together form a siphon in which the column 40 6 corresponds to one leg of the ordinary U-shaped siphon and the discharge pipe 12 corresponds to the other leg. When the water is forced up in the column 6 above the level of the pipe 12, the siphon will be 45 started and it will continue to flow until the water in the tank falls below the level of the opening 7'. The result of this siphon action is to draw all the water out of the chamber as fast as it flows into the same. 50 As a result, the pressure of the water in the tank outside will hold the diaphragm 15 away from the valve seat 9' so that the valve will be kept open until the tank is empty. The projections 14 prevent the disk 13 from 55 engaging snugly against the top of the casting 7 and sealing the bottom of the siphon.

It will readily be seen that instead of using the float 5 and the valve 4 for keeping the level of the water in the tank normally 60 below the top of the siphon discharge pipe 12, these parts might be dispensed with. In this case, the action of the valve would be automatic, and when the water in the tank had risen to a level above the top of the discharge pipe 12 the siphon would be started 65

automatically and would suck up the water from the chamber so as to lessen the pressure therein and cause the diaphragm 15 to be lifted by the pressure of the water in the tank. As a result, the flush valve would be 70 operated automatically as soon as the water had risen to a predetermined level in the tank.

It is immaterial whether I operate the valve from above or below and in Fig. I, I 75 have shown the valve as operated from above, while in Figs. V and VI, I have shown the same as operated from below. It will be noted in Fig. I that there is a loose connection between the link 20 and the operating rod 19 so that the link 20 may drop back into position while the rod 19 and the valve 80 18 are held in an elevated position. The same is true of the modification shown in Figs. V and VI, in which, on account of the 85 slot 27', the link 27 may drop back into its normal position while the rod 19' is held lifted.

I am aware that the particular embodiments which I have here shown are susceptible 90 of considerable variation without departing from the spirit of my invention and I, therefore, do not wish to be restricted to the same. However, I have found that these particular embodiments are to be preferred and I desire to claim the same specifically as well as broadly, as indicated by my appended claims.

Having thus described my invention, what I claim as new and desire to secure by Letters Patent is:

1. In a valve of the class described, the combination of a valve seat; a ring integral with said seat; discharge openings between said ring and said seat; a chamber having a restricted inlet supported on said ring; a siphon column extending upwardly from said chamber and sealed at its upper end; a diaphragm valve forming the bottom wall of said chamber and normally engaging said valve seat, said valve comprising a diaphragm; a disk disposed above said diaphragm; a plurality of projections struck up from said disk, and a disk disposed beneath said diaphragm; a siphon discharge pipe projecting into said siphon column, having its lower end threaded into said upper disk and passing through said disk and said diaphragm; a lower discharge pipe coupled to the lower end of said siphon discharge pipe and clamping said disk to said diaphragm; a rod connected to said diaphragm valve; and means for lifting said rod, all coacting substantially as described for the purpose specified.

2. In a valve of the class described, the combination of a valve seat; a suitably supported chamber having a restricted inlet opening; a siphon column extending upwardly from said chamber and sealed at its 130

upper end; a diaphragm valve forming the bottom wall of said chamber and normally engaging said valve seat, said valve comprising a diaphragm; a disk disposed above 5 said diaphragm; a plurality of projections struck up from said disk and a disk disposed beneath said diaphragm; a siphon discharge pipe projecting into said siphon column, having its lower end threaded into 10 said upper disk and passing through said disk and said diaphragm; a lower discharge pipe coupled to the lower end of said siphon discharge pipe and clamping said disk to said diaphragm; and means connected to 15 said diaphragm valve for raising the same, all coacting substantially as described for the purpose specified.

3. In a valve of the class described, the combination of a valve seat; a suitably supported chamber having a restricted inlet opening; a siphon column extending upwardly from said chamber and sealed at its upper end; a diaphragm valve forming the bottom wall of said chamber and normally 20 engaging said valve seat, said valve comprising a diaphragm and a disk disposed above said diaphragm, having a plurality of projections struck up therefrom; a siphon discharge pipe projecting into said siphon 25 column, having its lower end secured to said disk and passing through said disk and said diaphragm; means for clamping said disk to said diaphragm; and means connected to 30 said diaphragm valve for raising the same, all coacting substantially as described for the purpose specified.

4. In a valve of the class described, the combination of a valve seat; a suitably supported chamber having a restricted inlet 40 opening; a siphon column extending upwardly from said chamber and sealed at its upper end; a diaphragm valve forming the bottom wall of said chamber and normally engaging said valve seat, said valve comprising a diaphragm and a disk disposed 45 above said diaphragm; a siphon discharge pipe projecting into said siphon column, having its lower end secured to said disk and passing through said disk and said 50 diaphragm; means for clamping said disk to said diaphragm; and means connected to said diaphragm valve for raising the same, all coacting substantially as described for the purpose specified.

5. In a valve of the class described, the combination of a valve seat; a suitably supported chamber having a restricted inlet opening; a diaphragm valve forming the bottom wall of said chamber and normally 55 engaging said valve seat; a siphon column extending upwardly from said chamber and sealed at its upper end; a siphon discharge pipe projecting into said siphon column carried by said diaphragm valve and passing therethrough; and means connected to 60

said diaphragm valve for raising the same, all coacting substantially as described for the purpose specified.

6. In a valve of the class described, the combination of a valve seat; a suitably supported chamber having a restricted inlet opening; a diaphragm valve forming the bottom wall of said chamber and normally engaging said valve seat; a siphon column extending upwardly from said chamber and sealed at its upper end; a siphon discharge pipe having its upper end opening into the upper part of said siphon column; and means connected to said diaphragm valve for raising the same, whereby the level of 70 the water in said column is raised above the upper end of said siphon discharge pipe to start the siphon, all coacting substantially as described for the purpose specified.

7. In a valve of the class described, the combination of a valve seat; a chamber having a restricted inlet opening therein; a diaphragm valve forming the bottom wall of said chamber and normally engaging said valve seat; a siphon discharge pipe 85 having its upper end opening into said chamber near the top thereof; and means connected to said diaphragm valve for raising the same, whereby the level of the water in said chamber is raised above the upper 90 end of said siphon discharge pipe to start the siphon, all coacting substantially as described for the purpose specified.

8. In a valve of the class described, the combination of a valve seat; a chamber having a restricted inlet opening therein; a diaphragm valve forming the bottom wall of said chamber and normally engaging said valve seat; a siphon discharge pipe having its upper end opening into said chamber 100 near the top thereof; a rod connected to the upper surface of said diaphragm valve; and means for lifting the same, all coacting substantially as described for the purpose specified.

9. In a valve of the class described, the combination of a valve seat, a suitably supported chamber having a restricted inlet opening, a diaphragm valve forming the bottom wall of said chamber normally engaging said seat, a siphon column extending upward from said chamber and sealed at its upper end, a siphon discharge pipe opening into said chamber having its upper end extending into said column and its lower end 110 extending through said valve and means to actuate said diaphragm to cause the water to rise in said water column whereby the level in the water column is raised above the upper end of the siphon discharge pipe, all 115 coacting as specified.

10. The combination with a liquid-containing receptacle having an outlet connection presenting a valve seat, a casing connected to said outlet connection and having 120

a port opening into the receptacle, a valve formed as a diaphragm constituting a part of said casing and adapted to coöperate with said valve seat, said valve exposed to pressures in said casing and said receptacle, 5 a siphon constituted by two pipes one within the other, the outer pipe in communication with said casing and the inner pipe being connected to and passing through 10 said valve and a manually operable device

having an operative connection with said valve.

In witness whereof, I have hereunto set my hand and seal in the presence of two witnesses.

CARL H. ZWERMANN. [L.S.]
